UNITED STATES PATENT OFFICE.

WILLIAM EICHLERGER AND EDWARD WATSON, OF WOODHAVEN, NEW YORK.

POLISHING-MACHINE.

1,294,430.

Specification of Letters Patent. Patented Feb. 18, 1919.

Application filed February 25, 1918. Serial No. 219,037.

To all whom it may concern:

Be it known that we, WILLIAM EICHLERGER and EDWARD WATSON, citizens of the United States, and residing at Woodhaven, L. I., in the county of Queens and State of New York, have invented certain new and useful Improvements in Polishing-Machines, of which the following is a specification, such as will enable those skilled in the art to 10 which it appertains to make and use the same.

This invention relates to polishing machines, and particularly to machines of this class designed primarily for use in polishing floors; and the object of the invention is to 15 provide an improved machine of the class specified which is comparatively simple in construction, efficient in operation, and which may be easily and conveniently manipulated by hand, and by a single operator; a further object being to provide a machine of the class specified which, in addition, to serving as a floor polishing machine may 20 also be used for other purposes as will hereinafter appear; and with these and other objects in view the invention consists in a machine of the class specified, constructed and operated as hereinafter described and claimed.

30 The invention is fully disclosed in the following specification, of which the accompanying drawings form a part, in which the separate parts of our invention are designated by suitable reference characters in 35 each of the views, and in which:—

Figure 1 is a side view of our improved machine;

Fig. 2 a plan view thereof with part of the construction in section;

40 Fig. 3 a partial section on the line 3—3 of Fig. 2;

Fig. 4 a partial section on the line 4—4 of Fig. 2;

Fig. 5 a section on the line 5—5 of Fig. 2; 45 and

Fig. 6 a section on the line 6—6 of Fig. 3.

In the practice of our invention, as shown in the drawings, we provide a main yoke-shaped frame *a* having parallel front sides *a*², and which is tapered backwardly as 50 shown at *a*³ and in the rear end portion of which is mounted a roller *b*.

Centrally and transversely of the main frame *a* is mounted a main bearing roller *b*², and between the parallel side members *a*² of the main frame *a* is mounted a supple-

mental pivoted frame *c* having parallel side members *c*² connected by a horizontal base plate *c*³, and the frame *c* and side members *a*² of the main frame *a* are connected by 60 pivot pins *d* which are passed therethrough.

The top of the rear end portions of the sides *c*² of the supplemental frame are provided with outwardly directed ears *c*⁴ which bear on and overlap the side members *a*² of 65 the main frame, and spiral springs *d*² are connected with the rear ends of said side members *c*² as shown at *d*³ and with the side members *a*² of the main frame as shown at *d*⁴, and serve to normally hold the supplemental frame, or the ears *c*⁴ thereof in contact with the side members *a*² of the main frame. 70

An electric motor *e* is mounted on the horizontal base *c*³ of the supplemental frame 75 and the motor shaft *e*² is provided with a gear *e*³ which meshes with another gear *e*⁴ mounted on one side *c*² of the supplemental frame as shown at *e*⁵. The front end portions of the side members *c*² of the supplemental frame are provided with arc-shaped recesses *c*⁵ adapted to receive ball bearings *f* 80 which are held in position by arc-shaped caps *f*² pivoted to the bottom portions of the side members *c*² of the supplemental frame 85 at *f*³, and the top portions of which are detachably connected with said side members *c*² of the supplemental frame by bolts *f*⁴ having winged nuts *f*⁵ as clearly shown in Figs. 1 and 5 of the drawings, and this construction 90 securely holds the bearings *f* in place but permits the quick detachment thereof whenever necessary.

Mounted in the bearings *f* is a rotary brush or buffing device *g* comprising a drum 95 composed of a plurality of similar parts *g*² which are arc-shaped in form and the side edges of which are provided with outwardly directed flanges *g*³, which form between said parts when secured together longitudinal 100 spaces *g*⁴ in which are mounted strips of fibrous material *g*⁵, the outer edges of which are flanged as shown at *g*⁶. The separate parts of the drum *g*² with the fibrous strips *g*⁵ therebetween are held in position by end 105 caps *g*⁷ which thread onto the end portions of said parts, as clearly indicated in Figs. 2 and 3 of the drawings, said caps being provided with outwardly directed studs *g*⁸ which pass through the bearings *f*, and the 110 outer faces of which are provided with threaded recesses *g*⁹, one of which is shown

in Fig. 2. It will be noted that one end of the separate parts g^2 of the drum is provided with a left hand thread, while the opposite end is provided with a right hand thread, 5 which construction prevents the accidental displacement of said parts, or the loosening of their connection with the caps g^7 .

One of the caps g^7 is provided with a collar portion g^{10} to which is secured a gear h 10 which is adapted to mesh with the gear e^4 , as clearly indicated in Figs. 2 and 3 of the drawings. The studs g^8 of the caps g^7 extend beyond the sides of the supplemental frame c , and a supplemental rotary brush or 15 buffering device i comprising an annular flange portion i^2 of fibrous material secured between front and back plates i^3 and i^4 , is secured to one of the studs g^8 by a bolt i^5 which passes into the threaded recesses g^9 20 in the end of said stud.

The main frame a is provided between the rollers b and b^2 with inwardly directed members a^4 between which is pivoted a handle piece attaching block j with which 25 a handle member j^2 is adapted to be connected. The block j is provided with an upwardly directed lug j^2 which forms a bearing for a rod j^4 mounted to move longitudinally of the handle member j^2 and adapted 30 to be operated from the handpiece on the end of the handle member j^2 , said handpiece being not shown.

Connected with the lower end of the rod j^4 is a cross bar j^5 , to the ends of which are 35 pivotally connected one end of lever devices k pivoted to upwardly directed ears a^5 as shown at k^2 , the ears a^5 being integral with a transverse web member a^6 which joins the side members a^2 of the main frame a , as 40 clearly shown in Fig. 2. The other ends of the lever devices k are pivoted to links k^3 which are also pivoted to upwardly directed ears c^6 , as shown at k^4 , the ears c^6 , being integral with the base c^3 of 45 the supplemental frame as clearly indicated in Fig. 4 of the drawings, and with this construction by moving the rod j^4 downwardly, the inner end of the supplemental frame c may be raised against the tension 50 of the springs d^2 to bring the faces of the fibrous strips g^5 of the brush or buffering device g in contact with the floor, and the extent of this movement will be regulated by hand, as will be readily understood, and 55 suitable devices may be employed on the free end of the handle member j^2 to lock the rod j^4 in any desired position as will be readily understood, but as our invention is not limited to these details of construction 60 the same have not been shown.

A sheet metal housing m is preferably connected with the top of one side member c^2 of the supplemental frame c as clearly indicated in Fig. 4 and is adapted to 65 close the gears c^3 and c^4 to prevent dust,

and dirt, and other foreign matter from coming in contact therewith, but it will be understood that the entire apparatus may be inclosed in a sheet metal or other casing providing sufficient room is allowed for the slight movement of the pivoted supplemental frame c within the main frame a .

From the foregoing description, the operation of our improved apparatus will be readily understood when taken in connection with the accompanying drawings and the following statement. The normal position of the separate parts of the apparatus is indicated in the drawings or, in other words, the supplemental frame c is held

75

in contact with the main frame a under the tension of the springs d^2 and the faces of the fibrous strips g^5 employed in the rotary brush or buffering device g are supported above the floor, or out of operative connection therewith as clearly indicated in Fig. 1, provided the handle member j^2 is under the control of the operator, or is manipulated to move the apparatus over the floor, it being understood that when the apparatus

90

is idle the weight of the motor and the brush or buffering device g at the front of the machine will tilt said apparatus forwardly and the device g will make contact with the floor, while the roller b will be raised slightly, and when it is desired to use the apparatus, the fibrous material employed in said brush or buffering device is preferably saturated with a suitable fluid having cleansing and polishing qualities, after 100 which the motor e is put into operation in the usual manner, the electrical connections of said motor being not shown in the accompanying drawings for the reasons that they form no part of the invention, after 105 which the rod j^4 is moved downwardly to raise the inner end of the supplemental frame c against the tension of the springs d^2 to bring the brush or buffering device g into contact with the floor and the extent of 110 this movement is under the control of the operator and upon the release of the rod j^4 by the operator, the springs d^2 will return the supplemental frame c to its normal position.

115

In mounting the supplemental frame c in the manner shown and described, the operation of the brush or buffering device g in connection with the floor will be more or less tensionally controlled, and this will prevent 120 the binding of said brush or buffering device g , which operation would stop the motor e and be objectionable, and by providing a detachable mounting for the brush or similar device g in the side c^2 of the supplemental 125 frame different brushes may be quickly attached and detached from the supplemental frame whenever desired, it being understood that one brush may be employed for applying the liquid substance employed for 130

cleansing and polishing while another brush may be employed for finishing the polishing operation, the latter being free from the liquid substance, and while we have described 5 the apparatus as particularly used for the purpose of polishing floors, it will be understood that brushes or other rotary devices of any kind or class may be connected with the supplemental frame *c* for the purpose of 10 scouring or cleaning floors, while sand-stone or emery rollers may be employed for the purpose of planing or cleaning floor surfaces prior to painting, varnishing or polishing the same, in which latter event the apparatus 15 will be suitably constructed to do such work, a stronger framework being necessary as well as a motor of greater power, and it will be understood that our invention is not limited to the details of construction herein 20 shown and described for mounting and operating the separate parts of our apparatus, and changes in and modifications of such details of construction may be made, within the scope of the appended claims, without 25 departing from the spirit of our invention or sacrificing its advantages.

In Fig. 2 of the drawing we have shown a supplemental rotary brush or buffing device *i* connected with one of the studs *g*⁸ and 30 indicated another of said devices connected with the other stud *g*⁸ in dotted lines, and it will be understood that one of said devices may be connected with either of said studs whenever desired, or both of said studs may 35 be provided with one of said brush or buffing devices *i*. The purpose of these devices is to enable the operator of the machine to clean or polish the floor adjacent to the baseboards of the walls or around corners, or 40 objects in a room.

Having fully described our invention, what we claim as new and desire to secure by Letters Patent, is:—

1. In an apparatus of the class described, 45 a main frame approximately yoke-shaped in form and comprising a back portion, forwardly and outwardly directed side portions and a top central web portion, a roller mounted in the back portion of the frame, 50 another roller mounted between the forwardly and outwardly directed side portions of the frame, and a handle device pivoted to said frame between said rollers, a supplemental frame pivoted to the end portions 55 of the forwardly and outwardly directed side portions of the frame, a rotary member mounted in connection with the supplemental frame, an electric motor mounted in the supplemental frame, a gear mounted on the 60 motor shaft, a gear mounted on one end portion of the rotary member and a gear mounted on the supplemental frame and in operative connection with said first named gears.
2. In an apparatus of the class described, 65 a main frame approximately yoke-shaped in form and comprising a back portion, forwardly and outwardly directed side portions and a top central web portion, a roller mounted in the back portion of the frame, 70 another roller mounted between the forwardly and outwardly directed side portions of the frame, and a handle device pivoted to said frame between said rollers, a supplemental frame pivoted to the end portions of the forwardly and outwardly directed side portions of the main frame, a rotary member mounted in connection with the supplemental frame, an electric motor mounted in the supplemental frame, a gear mounted on the motor shaft, a gear mounted on one end portion of the rotary member and a gear mounted on the supplemental frame and in operative connection with said first named gears, the supplemental frame being 75 provided at its opposite sides and adjacent to the inner end portion thereof with outwardly directed lugs adapted to engage the side portions of the main frame, tensional devices connected with the opposite sides 80 of the supplemental frame at the inner end thereof and with the main frame and serving to hold said supplemental frame in engagement with the main frame, lever devices pivoted to the top web portion of the main frame, one of said levers being pivoted to the inner end portion of the supplemental frame and an operating rod mounted to move longitudinally of the handle member and in operative connection with the other 85 end portions of said levers.
3. In an apparatus of the class described, a main yoke-shaped frame, comprising a back member, forwardly and outwardly directed side members and a top web member, a roller mounted in the back member of the main frame, another roller mounted between the side members of said frame, a handle member pivoted to said frame between said rollers, a supplemental frame pivoted to the front end portion of the side members of the main frame, a rotary member detachably connected with the supplemental frame, an electric motor mounted in said frame, 90 gears for placing said motor and rotary member in operative connection, levers pivoted to the top web member of the main frame, one end of said levers being pivoted to the supplemental frame and an operating rod mounted to move longitudinally of the handle member and in operative connection with the other end portions of said levers.
4. In an apparatus of the class described, a main yoke-shaped frame, comprising a back member, forwardly and outwardly directed side members and a top web member, a roller mounted in the back member of the main frame, another roller mounted between the side members of said frame, a handle member pivoted to said frame be- 100

- 2:5
 tween said rollers, a supplemental frame pivoted to the front end portion of the side members of the main frame, a rotary member detachably connected with the supplemental frame, an electric motor mounted in said frame, gears for placing said motor and rotary member in operative connection, levers pivoted to the top web member of the main frame, one end of said levers being pivoted to the supplemental frame, an operating rod mounted to move longitudinally of the handle member and in operative connection with the other end portions of said levers, the supplemental frame being provided with lugs adapted to engage the main frame and tensional means for holding said lugs in engagement with said main frame. 5. In an apparatus of the class described, a main frame comprising a back member, forwardly directed side members and a top member, a roller mounted in the back member of the main frame, another roller mounted between the side members of said frame centrally thereof, a handle member pivoted to said frame between said rollers, a supplemental frame pivoted to the front end portion of the side members of the main frame, said supplemental frame comprising a bottom member and forwardly directed side members, bearings mounted in the front end portions of the side members of the supplemental frame, a rotary member mounted in said bearings, said rotary member being provided with oppositely directed trunnions, an electric motor mounted on the bottom member of the supplemental frame, gears for placing said motor and rotary member in operative connection, levers pivoted to the top member of the main frame, one end of said levers being pivoted to the supplemental frame; an operating rod mounted to move longitudinally of the handle member and in operative connection with the other end portion of said levers, the supplemental frame being provided at the inner end portion thereof with means for limiting the downward movement of said supplemental frame in the main frame, tensional means for holding the supplemental frame against upward movement in the main frame, and supplemental rotary members detachably connected with the trunnions of the first named rotary member. 7. In an apparatus of the class described, a main frame, comprising a back member, forwardly directed side members and a top member, rollers mounted between said side members for supporting said frame, a handle member pivoted to said frame between said rollers, a supplemental frame pivoted to the front end portions of the main frame, a rotary member detachably connected with the front end of said supplemental frame, an electric motor mounted in said supplemental frame, means for gearing said motor in connection with said rotary member, lever devices pivoted to the top member of the main frame, said lever devices being in operative connection with said supplemental frame and an operating rod mounted to move longitudinally of said handle member and in operative connection with said lever devices whereby the pressure of the rotary member on the floor may be controlled. 6. In an apparatus of the class described, a main frame comprising a back member, forwardly directed side members and a top member, a roller mounted in the back member of the main frame, another roller mounted between the side members of said frame centrally thereof, a handle member pivoted to said frame between said rollers, a supplemental frame pivoted to the front end portion of the side members of the main frame, said supplemental frame comprising a bottom member and forwardly directed side members, bearings mounted in the front end portions of the side members of the supplemental frame, a rotary member mounted in said bearings, said rotary member being provided with oppositely directed trunnions, an electric motor mounted on the bottom member of the supplemental frame, gears for placing said motor and rotary member in operative connection, levers pivoted to the top member of the main frame, one end of said levers being pivoted to the supplemental frame; an operating rod mounted to move longitudinally of the handle member and in operative connection with the other end portion of said levers, the supplemental frame being provided at the inner end portion thereof with means for limiting the downward movement of said supplemental frame in the main frame, tensional means for holding the supplemental frame against upward movement in the main frame, and supplemental rotary members detachably connected with the trunnions of the first named rotary member. 8. In an apparatus of the class described, a main frame, comprising a back member, forwardly directed side members and a top member, rollers mounted between said side members for supporting said frame, a handle member pivoted to said frame between said rollers, a supplemental frame pivoted to the front end portions of the main frame, a rotary member detachably connected with the front end of said supplemental frame, an electric motor mounted in said supplemental frame, means for gearing said motor in connection with said rotary member, lever devices pivoted to the top member of the main frame, said lever devices being in operative connection with said supplemental frame and an operating rod mounted to move longitudinally of said handle member and in operative connection with said lever devices whereby the pressure of the rotary member on the floor may be controlled.

In testimony that we claim the foregoing as our invention we have signed our names in presence of the subscribing witnesses this 15th day of February, 1918.
